[57] CLAIM

The ornamental design for a vehicle grille valance cover, as shown and described.

DESCRIPTION

FIG. 1 is a perspective view of a vehicle grille valance cover embodying my new design, the front perspective of a vehicle being shown fragmentally to show the environment in which the vehicle grille valance cover is used, the broken lines being for illustrative purposes only, and forming no part of the claimed design.

FIG. 2 is a perspective view of the vehicle grille valance cover.

FIG. 3 is a front elevational view of the vehicle grille valance cover.

FIG. 4 is a top plan view of the vehicle grille valance cover.

FIG. 5 is a right side view of the vehicle grille valance cover, the left side view being a mirror image thereof.

FIG. 6 is a rear elevational view of the vehicle grille valance cover; and,

FIG. 7 is a bottom plan view of the vehicle grille valance cover.
